[57] CLAIM

The ornamental design for a physical exercise stool, as
shown and described.

DESCRIPTION

FIG. 1 is a perspective view of a physical exercise stool
showing my new design;

FIG. 2 is a left side elevational view thereof, the side
opposite being a mirror image;

FIG. 3 is a front elevational view thereof, the side oppo-
site being a mirror image;

FIG. 4 is a top plan view thereof; and,

FIG. 5 is a bottom plan view thereof.
